PUSH BACK THEATRE SEAT

Jacques Ducharme, Montreal, Quebec, Canada, assignor to O. Ducharme & Fils Limitee, Montreal, Quebec, Canada

Filed June 30, 1965, Ser. No. 85,955

Term of patent 14 years

(Cl. D15—8)

Fig. 1

The side of the chair, not shown, is like the side shown, while the back is plain and unornamented.

I claim:

The ornamental design for a push back theatre seat, as shown and described.
